UNITED STATES PATENT OFFICE

JOHN H. BRADLEY, OF PHILADELPHIA, PENNSYLVANIA.

THERAPEUTICAL DEVICE.

1,134,720.

Specification of Letters Patent.

Patented Apr. 6, 1915.

Application filed May 28, 1914. Serial No. 841,623.

To all whom it may concern:

Be it known that I, JOHN H. BRADLEY, a citizen of the United States, residing in Philadelphia, Pennsylvania, have invented 5 certain Improvements in Therapeutical Devices, of which the following is a specification.

This invention relates to therapeutical and comfort apparatus, and the object of the 10 invention is to provide means for enabling persons affected with heart disease, diseases of the lungs, or other afflictions rendering rest in recumbent positions difficult, to sleep and to rest without the necessity of lying in 15 a prone position.

As is well known, any prone posture affects more or less seriously the action of the heart, and this structure has been devised 20 with a view of enabling persons suffering from heart and lung affections to sleep while in a sitting posture.

The structure is also available for use as a table for the serving of meals to the patient; as a desk for reading, writing and 25 amusement, and as a support for medicine or for apparatus used in treating a patient.

These and other features of the invention are more fully described hereinafter, reference being had to the accompanying drawings, in which:

Figure 1, is a perspective view showing the apparatus in use; Fig. 2, is a view of the apparatus partially detached from its supporting means, which latter are shown as 35 carried by a bed; Fig. 3, is a front elevation of the apparatus shown in Figs. 1 and 3, and Figs. 4 and 5, are views illustrating details of the invention.

The improved structure comprises a table 40 1, upon which the arms of the patient may rest, and a head-rest 2, as shown in Fig. 1. The table 1 is provided with brackets or supports 3, having hubs 4, adjustably adapted to adjustable bars 5, which bars may be 45 carried by posts 6 vertically adjustable in yoke frames 7 carried by the side rails 8 of the bed, and which are adjustable thereon. The hubs 4 are secured to the bars 5 by locking screws 9, and said bars 5 are detachably 50 connected with the posts 6; the latter having a flattened portion 10 adapted to a notched or slotted portion 11 carried by the bar 5 which also carries a locking screw 12 to secure the parts together when in a connected position.

The several supporting parts of the struc-

ture are made adjustable so that the table portion 1 may be raised or lowered, as may be desired, to suit patients of different size, and may also be adapted to beds of different width. The joint formed between the bar 5 and the post 6 forms a hinge permitting the table to be moved to positions at greater or less angles to the horizontal, as may be found desirable for the comfort or 65 convenience of the patient when resting or sleeping. The table may be held in such adjusted position by means of the locking screws 12. The bars 5 are swiveled to their notched or slotted portions 11 so that the 70 table may be locked in a horizontal position by moving the joint formed by the parts 10 and 11 to a position at right angles to that shown in Fig. 1, as illustrated in Fig. 3.

The head-rest 2 is pivotally connected to 75 an arm 15 adjustable in a support 16, being held in position by a locking or set screw 17, and this support has a post 18 which is adjustable vertically in a socketed support 19 detachably carried by the table; being re- 80 tained in position by a set screw 20 when the desired adjustment is made.

To accommodate different width beds and increase the range of adjustment, the yoke frames may be made as shown at 7^a in Fig. 85 4, where they are shown as turned outwardly with respect to the side of the bed-frame. When turned inwardly a wider adjustment is provided without the necessity of changing the connection of the bar 5 90 with the hub 4 of the bracket carried by the table 1.

Various forms of means for attaching the table supporting structure to beds of any construction may be provided, without departing from my invention, and such structure should be adjustable vertically as well as toward and from the patient in order that the latter, no matter what his proportions may be, may be enabled to find a positively 100 comfortable position with the least effort.

While this structure has been devised more particularly for hospital use, it is not limited thereto, nor is its use limited to a connection with a bed. With but slight 105 modification; involving no change in the invention, the structure may be applied to chairs of various types.

I claim:

1. The combination with a bed frame, of 110 laterally and vertically adjustable brackets carried by the side rails thereof, a detach-

- able table adjustably supported by said brackets, said table forming an arm-rest, and a head-rest centrally disposed with respect to and detachably carried by said table.
- 5 2. A therapeutic device designed to induce sleep, comprising laterally and vertically adjustable supporting means, a table detachably connected thereto and forming an arm-rest, and an adjustable head-rest centrally disposed with respect to and detachably carried by said table.
- 10 3. The combination with a bed frame, of a table adjustably supported laterally and vertically by said bed frame, detachable

hinge connections between said table and 15 the bed frame, said table forming an arm-rest, means for locking said table in adjustable angular positions, and an adjustable head-rest centrally disposed with respect to and detachably carried by said table. 20

In testimony whereof, I have signed my name to this specification, in the presence of two subscribing witnesses.

JOHN H. BRADLEY.
